C. L. DUNHAM

UNDERREAMER

Filed Feb. 12, 1925

UNITED STATES PATENT OFFICE.

CHARLES L. DUNHAM, OF PENNSBORO, WEST VIRGINIA.

UNDERREAMER.

Application filed February 12, 1925. Serial No. 8,772.

To all whom it may concern:

Be it known that I, CHARLES L. DUNHAM, a citizen of the United States, residing at Pennsboro, in the county of Ritchie and 5 State of West Virginia, have invented certain new and useful Improvements in Underreamers; and I do declare the following to be a full, clear, and exact description of the invention, such as will enable others 10 skilled in the art to which it appertains to make and use the same.

My invention relates to improvements in underreamers, used primarily in connection with well casings of oil wells, when it is 15 necessary to lower such casings.

While numerous underreamers have been heretofore devised and used, they are open to certain objections. For instance, one well known type of underreamer which relies totally upon a key to retain all working 20 parts within the body, often loses or breaks the key, so that all working parts of the reamer fall to the bottom of the well and cause almost endless trouble in fishing them 25 out. In fact, very often, the well must be abandoned and another drilled adjacent thereto. While other types of reamers have been used with some degree of success, they 30 are complicated and expensive, and they contain so many parts requiring milling or other machining, that the cost of manufacture is excessive. Moreover, these complicated devices are liable to get out of order 35 and cause a great deal of trouble.

It is the object of my invention to provide an underreamer of extreme simplicity, which may be manufactured at small cost, yet will be efficient, reliable, long-lived, and in every way desirable.

With the foregoing in view, the invention resides in the novel subject matter hereinafter described and claimed, the description being supplemented by the accompanying drawings.

Figure 1 is a vertical sectional view of an underreamer constructed in accordance with my invention, showing the relation of parts when the device is being either raised or lowered through a well casing.

Figure 2 is a duplicate of Fig. 1 with the exception that it illustrates the movable parts of the device in position for operation of the reamer.

Figures 3 and 4 are transverse sectional

views as indicated by lines 3—3 and 4—4 of 55 Fig. 2.

Figure 5 is an inner side elevation of one of the cutters and its shank.

In the drawings above briefly described, the numeral 1 designates a vertically elongated body whose upper end is provided with the usual plug 2 for engagement with a socket 3 or any means which may be used for operating the reamer. From its lower end, to a point a suitable distance above 60 said end, the body 1 is formed with a central longitudinal bore 4 which is of uniform diameter throughout its length, instead of being of stepped form, as in certain other types of reamers. By having the bore of 65 this uniform diameter throughout its length, a great saving in time is effected during the manufacture of the tool and consequently a 70 saving in cost is effected. Near its lower end, the body 1 is formed with a pair of opposed vertical slots 5, each of which extends throughout its entirety, from the interior 75 to the exterior of the body. These slots 80 may be rapidly and easily formed with ordinary shop equipment, whereas the types of slots employed in certain other forms of reamers require a considerably greater amount of machining, consequently adding 85 to cost of production.

Two cutters 6 are disposed under the body 1, and their upper ends 8 are adapted to abut the lower end of said body, substantially throughout the circumference of the latter, when said cutters are extended for use as shown in Fig. 2. Thus, substantially 90 continuous knocking shoulders are provided which take all strain from the pivot means by which the shanks 9 are mounted in the lower end of the bore 4. These shanks are integral with the upper ends of the cutters 95 6 and they are pivotally mounted in a unique manner hereinafter described in detail.

The shanks 9 are provided with beveled upper ends 10 disposed between the slots 5, said slots receiving a pair of pivotally mounted dogs 12 having portions 13 projecting into the bore 4 and normally lying against the beveled ends 10, as shown in 100 Fig. 1. These projecting portions 13 of the dogs however, are formed with angular notches 14 which provide shoulders to engage the shanks 9 and lock the cutters 6 in 105

the extended position shown in Fig. 2, movement of the dogs to the position of the last named figure, serving to project said cutters. For moving the dogs in this manner, 5 a head 15 is slidable in the upper portion of the bore 4 and is forced normally in a downward direction by the action of a compression spring 17 which is confined between the upper end of said bore and said 10 head. Heretofore, whereas heads corresponding to the head 15 have commonly been slidably mounted in bores and held in some manner against rotation, the construction of my invention is such that the afore- 15 said head 15 may be free to rotate in the bore, and may be of truly cylindrical form, so that it may be readily turned upon an ordinary lathe. The lower end of this head is formed with a shallow recess having an 20 inwardly inclined, annular, cam surface 17 which engages the upwardly converging edges 18 of the dog portions 13, when the parts stand as shown in Fig. 1. By having the surface 17 of annular form, it will co- 25 operate properly with the edges 18, regardless of the position to which the head 15 may turn, it being therefore unnecessary to provide any expensive means to hold this head against rotation.

30 When the device is being lowered through a well casing, as shown in Fig. 1, the dogs 12 are within the confines of the body 1 and the cutters 6 are held in retracted position by contact of their enlargements 19 35 with the well casing. As soon as the cutters 6 and dogs 12 have been lowered sufficiently to free the casing however, the head 15 is downwardly shifted by the spring 16, and the co-acting cam surfaces 17 and 18 40 then swing the upper ends of the dogs 12 inwardly to the position shown in Fig. 2, and during this inward movement, the portions 13 of said dogs force the upper ends of the shanks 9 together, thus spreading the cutters 6 to operative position. As soon as the 45 cutters have reached this position, the notches 14 of the dogs 12 have snugly received the upper ends of the shanks 9, and as said dogs are held in this position by the 50 spring-pressed head 15, they will positively lock the cutters in position for operation.

Upon withdrawal of the device from the well, the lower ends 20 of the dogs 12 strike the lower end of the casing and thus these 55 dogs are rocked, so that the co-acting cam surfaces 17 and 18 will force the head 15 upwardly against the action of the spring 16. This movement of the dogs also frees the upper ends of the shanks 9, so that when 60 the enlargements 19 of the cutters 6 come in contact with the casing, said cutters may move inwardly and readily enter said casing.

As above suggested, a unique pivotal mounting means for the shanks 9 has been 65 shown, this mounting means being of such

construction that it may be easily and inexpensively manufactured, will be exceptionally strong and durable in use, and will act to plug the lower end of the bore 4 against the entrance of an excessive amount 70 of mud or other foreign matter. Each shank 9 is of substantially semi-conical form, and at its lower end, half the width of each shank is cut away by an ordinary planer or shaper to provide a recess 21 having straight, converging, upper and lower, edge walls 22 and a flat vertical side wall 23. Each shank 9 is provided at its lower portion with a laterally extending lug 24 having straight, converging, upper and 80 lower edges 25 and a vertical side which is flush with or in the same plane with the side wall 23 of the recess 21. From the plane of the surface 23 to one vertical edge of each cutter 6, the latter is provided with a beveled rib 26, and from said plane to the opposite vertical edge of the cutter, the latter is formed with a bevel 27. The two shanks 9 and their lateral lugs 24 jointly form a substantially conical 90 structure which plugs the lower end of the bore 4 as shown in the drawing, when the cutters are expanded for use, and it will be seen from Figs. 1 and 2 that the lug 24 of each shank is received in the recess 21 of the other shank, the flat vertical faces of said lugs and recesses being in contact with each other. Moreover, it will be seen that the beveled rib 26 of each cutter 6 overlies the bevel 27 of the other cutter.

To mount the shanks in the bore 4, a pivot pin or screw 28 passes transversely through the lower end of the body 1 and passes also through the lugs 24. When the reamer is in use, there is no strain upon this pivot, on account of the continuous knocking shoulders 8 which engage the lower ends of the body 1, substantially throughout the circumference of the latter. Thus, there is no danger of the pivot shearing and permitting the cutters to drop into the well. If either of the shanks should break and a cutter be lost, no other parts of the reamer may descend also and thus it is only necessary to fish for the lost cutter instead of for a multiplicity of parts as is very often necessary in connection with types of reamers now on the market.

Each cutter 6 and its integral shank 9, 120 may be formed by drop forging, and the finishing of these parts may be accomplished upon an ordinary lathe, and a shaper or planer, it being unnecessary to use any expensive milling machine work in the construction of the improved reamer.

Excellent results are obtainable from the details disclosed and they may therefore be followed. However, within the scope of the invention as claimed, modifications may of course be made.

I claim:

1. An underreamer comprising a vertically elongated body having a central longitudinal bore which opens through its lower end, said body also having a pair of opposed vertical slots near its lower end, a pair of cutters under the body having shanks extending into the aforesaid bore and pivoted to said body, a pair of dogs 5 pivotally mounted in the aforesaid slots and co-acting directly with the upper ends of said shanks to lock the cutters in expanded position, and a spring-lowered head slidable in the aforesaid bore over the dogs, said head being co-operable with said dogs to force the same to cutter-locking position when expansion of the cutters is permitted, and to hold said dogs in cutter-locking position while operating the reamer, said dogs 10 having portions adapted to strike the lower end of a well casing to move them to cutter-releasing position and to raise the aforesaid head when the reamer is withdrawn from a well.
2. An underreamer comprising a vertically elongated body having a central longitudinal bore which opens through its lower end, said body also having a pair of opposed vertical slots near its lower end, a pair of cutters under the body having shanks extending into the aforesaid bore and pivoted to said body, a spring-lowered dog-actuating and holding head slidable in said bore adjacent the upper ends of said slots, and a pair of dogs pivotally mounted in said slots and having portions interposed directly between and in contact with said head and said shanks, said dogs having abrupt shoulders adapted to engage said shanks 15 and lock the cutters in expanded position when said dogs are moved to operative position by said head, the dogs being provided with other portions adapted to strike the lower end of a well casing to move them to cutter-releasing position and to raise the aforesaid head when the reamer is withdrawn from a well.
3. An underreamer comprising a vertically elongated body having a central longitudinal bore which opens through its lower end, said body also having a pair of opposed vertical slots near its lower end, a pair of cutters under the body having shanks extending into the aforesaid bore and pivoted to said body, a pair of dogs pivotally mounted in the aforesaid slots and co-acting directly with the upper ends of said shanks to lock the cutters in expanded position, and a spring-lowered head slidable in the aforesaid bore over the dogs, said head having an annular cam surface engaging said dogs to move the latter to cutter-locking position when the cutters are permitted to expand regardless of the position to which said head may have turned about a vertical contact; and a pivot pin passing transversely 20
- axis, said dogs having portions adapted to strike the lower end of a well casing to move them to cutter-releasing position and to raise the aforesaid head when the reamer is withdrawn from a well. 70
4. An underreamer comprising a cylindrical body having a longitudinal bore of uniform diameter throughout its length and opening through its lower end, said body being also provided with a pair of opposed vertical slots near its lower end and extending in their entirety from the exterior to the interior of the body, a pair of cutters adapted to abut the lower end of the body and having shanks which extend into the aforesaid bore and are pivoted to said body, said shanks having upwardly beveled upper ends disposed between the aforesaid slots, a pair of flat cutter-locking dogs pivoted in said slots and having inwardly projecting portions to rest on said beveled ends of said shanks when the cutters are contracted, said inwardly projecting portions having angular notches to engage the cutter shanks and lock the same when the cutters are expanded and being also provided with upper ends which converge upwardly when the dogs are in released position, a cylindrical dog-actuating head slidable in the aforesaid bore and having a recess in its lower end provided with an inwardly inclined annular wall engaging said upwardly converging upper ends of said inwardly projecting dog portions, and a coiled compression spring 75 interposed between the upper end of the aforesaid bore and said head and adapted to force the latter downwardly to move the dogs to cutter-locking position when expansion of the cutters is permitted, said dogs having portions adapted to strike the lower end of a well casing to move them to cutter-releasing position and to raise the aforesaid head when the reamer is withdrawn from a well. 80
5. An underreamer including a body having a bore which opens through its lower end; a pair of cutters whose upper ends abut the lower end of said body substantially throughout the circumference of the latter when said cutters are expanded; substantially semi-conical upstanding shanks integral with the upper ends of said cutters and each having half its width cut away near its lower end to provide a recess having straight converging upper and lower edge walls and a flat vertical side wall, each of said shanks being provided with an integral lateral lug having upper and lower straight converging edges, said lug also having a flat inner vertical side in the same plane with said vertical side wall of the recess; the lug of each shank being received in the recess of the other shank with the above-named flat portions of the two shanks in 85
- 100
- 105
- 110
- 115
- 120
- 125
- 130

through the aforesaid body and through the lugs of said shanks; said shanks and their lugs jointly plugging the lower end of the aforesaid bore against appreciable entrance of foreign matter.

5. A structure as specified in claim 5; each cutter having a beveled rib at the upper end of its inner side from the flat side of its

lug to one vertical edge of the cutter, each cutter having also a bevel from said flat side of its lug to its other vertical edge; the beveled rib of each cutter overlying the bevel of the other cutter.

10 In testimony whereof I have hereunto affixed my signature.

CHARLES L. DUNHAM.
